(57) **CLAIM**

The ornamental design for a storm water drainage pit, as shown.

DESCRIPTION

FIG. 1 is a front side and one end perspective view of the storm water drainage pit in accordance with an embodiment of the present invention;

FIG. 2 is a bottom and second end perspective view of the storm water drainage pit in accordance with an embodiment of the present invention;

FIG. 3 is a top plan view of the storm water drainage pit in accordance with an embodiment of the present invention;

FIG. 4 is a bottom plan view of the storm water drainage pit in accordance with an embodiment of the present invention;

FIG. 5 is an end elevation view of one end of the storm water drainage pit in accordance with an embodiment of the present invention;

FIG. 6 is an opposite end elevation view of one end of the storm water drainage pit in accordance with an embodiment of the present invention;

FIG. 7 is a side elevation view of one side of the storm water drainage pit in accordance with an embodiment of the present invention; and,

FIG. 8 is an opposite side elevation view of one side of the storm water drainage pit in accordance with an embodiment of the present invention.

The broken line showing in FIG. 3 is included for the purpose of illustrating portions of the article and forms no part of the claimed design.
